DESIGN FOR A WRIST WATCH

Israel L. Bloom, Denver, Colo.

Application September 5, 1936, Serial No. 64,738

Term of patent 14 years

To all whom it may concern:

Be it known that I, Israel L. Bloom, formerly a subject of the Czar of Russia, now the Union of Soviet Socialist Republics, residing at Denver, in the county of Denver and State of Colorado, United States of America, have invented a new, original, and ornamental Design for a Wrist Watch, of which the following is a specification, reference being had to the drawing, forming a part thereof.

Fig. 1 is a plan view of the front of a wrist watch showing my new design. Fig. 2 is a right edge view of Fig. 1. Both views are on a greatly enlarged scale.

The characteristic features of the design are the mutual conformity of the outline or shape of the dial and of the exterior contour of the watch case, both being heart shaped; the combination of the mutually conforming heart shaped exterior and dial with the arrow piercing the heart in the position shown, whereby the arrow will align itself with a wrist band when the watch is used as a wrist watch, and the placement of a winding stem of the type shown between the lobes of the heart shaped casing.

I claim:

The ornamental design for a wrist watch, as shown and described.

ISRAEL L. BLOOM.
